UNITED STATES PATENT OFFICE.

DELIA K. HAWLEY, OF CHICAGO, ILLINOIS, ASSIGNOR TO THE RATHBUN MANUFACTURING COMPANY, OF SAME PLACE.

AUTOMATIC LIGHTER.

SPECIFICATION forming part of Letters Patent No. 602,045, dated April 5, 1898.

Application filed September 17, 1897. Serial No. 651,971. (No model.)

To all whom it may concern:

Be it known that I, DELIA K. HAWLEY, a citizen of the United States, residing at Chicago, in the county of Cook and State of Illinois, have invented certain new and useful Improvements in Automatic Lighters, of which the following is a full, clear, and exact specification.

My invention relates to automatic lighters of that class in which the fulminate or other ignitable heads, which for the sake of convenience I shall hereinafter term "matches," are arranged in a box or receptacle and caused to ignite as they are automatically forced therefrom by a suitable ejector, and it has more especial reference to that species of such class in which a plurality of the matches are secured to a continuous strip.

My invention has for its primary object to provide an improved construction of automatic lighter in which a large supply of the matches may be contained and when desired simultaneously ejected and ignited and while burning held in a convenient position for use.

A further object of my invention is to automatically sever the burned match from the remaining unburned strip as the ejector is withdrawn; and a still further object is to provide, in connection with an automatic lighter, a plurality of matches, each consisting of a substantial body portion composed of inflammable material and an igniting portion for setting the latter afire, so constructed and arranged that the burning of one of the body portions will substantially sever or disintegrate its connection with the remainder of the strip, whereby the burned portion may be readily dislodged when the flame is no longer needed.

With these ends in view my invention consists in certain features of novelty in the construction, combination, and arrangement of parts by which the said objects and certain other objects hereinafter appearing are attained, all as fully described with reference to the accompanying drawings.

In the said drawings, Figure 1 is a plan view of my improved lighter, showing the lid of the box open and the ejector in readiness to force a match therefrom. Fig. 2 is a similar view, on a smaller scale, showing the lid

closed. Fig. 3 is a transverse sectional view taken on the line 3 3, Fig. 1. Fig. 4 is a detailed detached view of the ejector. Fig. 5 is a detail transverse sectional view taken on the line 5 5, Fig. 1. Fig. 6 is a longitudinal sectional view taken on the line 6 6, Fig. 1. Fig. 7 is a detail view of the spring-holding dog hereinafter explained; and Fig. 8 is a detail view of a portion of the match-strip, illustrating a certain modification hereinafter explained.

In carrying out my invention I employ a box 1, which is preferably of just sufficient depth to contain the match-strip 2 when arranged on edge therein in the manner shown in Fig. 1, one end of the box 1 being utilized as a receptacle in which the match-strip 2 may be folded back and forth in a zigzag form, as illustrated in the drawings, or arranged in any other desired way; but when arranged as shown a large number of the matches may be stored in the box, and the end one may be readily drawn off from one end of the zigzag series by the ejector without disturbing the others. The match-strip 2 may be composed of stout paper or any other suitable flexible material, and arranged at short intervals thereon are a plurality of matches, each consisting of a body portion 3, composed of some suitable inflammable material, and an igniting portion 4 for setting the inflammable material on fire. These matches 3 are also, preferably, of substantially the same thickness as the depth of the box 1, whereby the lid of the box when closed will hold them in place and guard against the possibility of the strip becoming twisted.

Arranged to reciprocate along one side of the box 1 is an ejector 5, which is provided at its upper end with a portion 6, preferably pointed, so as to dig into the matches 3 4 or engage in a cavity 7, specially formed in the back of each match, and thus enable the ejector to carry the match upward or outward to the end of the box, as well as hold it in place while being used.

In loading the device and making it ready for use one end of the match-strip is carried upwardly along the outer side of the ejector 5, and the end match 3 4 is located between the point 6 of the ejector and a yielding guide-

spring 8, which tends to hold the upper end of the match against the side of the box 1 and to also retain it in firm contact with the ejector in the manner illustrated in Fig. 1. If 5 now the ejector 5 is forced upwardly or outwardly, the end of the match 34 will be forced between an igniting-point 9 and the side of the box, and as it passes such igniting-point 9 the latter causes the head 4 to ignite and 10 set the body portion 3 on fire, which by this time has been carried entirely outside of the box by means of the ejector 5, where it is held by the point 6 until consumed. The match 34 in passing upwardly between the 15 side of the box and the igniter 9 comes in contact with a shoulder 10, turned inwardly and across the line of movement of the match, so that the latter in order to pass such inner portion of the igniter must deflect the igniter to one side or toward the opposite side of the box 1, which, as shown in dotted lines in Fig. 1, is in the form of a spring-tongue 11, bent inwardly, so as to be impinged by the inner portion 10 of the igniter when the latter is deflected, as described, by the match. 20 By this means the spring-tongue 11 is also forced outwardly and the upper end of the box opened to permit the match to pass out without compelling the igniting-head of the 25 match to scrape against the end of the tongue or any portion of the box. After the match has passed out clear of the end of the box and the igniter, the pressure against the spring-tongue 11 being released, the latter again 30 closes in to its normal position between the rear end of the match-body and the igniter, and as the ejector 5 is withdrawn the upper end of the tongue 11 strips the match from the point 6, and in so doing causes the burned 35 match to be dislodged and drop off. When the ejector reaches the limit of its inward movement, the point 6 thereof will be opposite and engage in the cavity 7 of the next match, which latter is held against moving 40 downwardly with the ejector by means of a spring-dog 12, preferably formed on the spring 45 8 in such a manner as to permit the matches to pass upwardly, but arrest their retrograde movement.

50 The ejector 5 is preferably composed of a flat strip (shown in detail in Fig. 4) having the point 6 formed on one end and a slide 13 bent over one side in such a manner that it may be engaged over the edge of the box 1, 55 as clearly shown in Figs. 1 and 3, so as to be accessible to the thumb or finger of the user from the outside when the box is closed, the lid of the box being cut away along the line of movement of the slide 13, so as to constitute a slot 14 between the edge of the lid and box, as shown in Fig. 2. When the lid of the 60 box is closed, the ejector will be held against dislodgement by the lid resting against that portion of the ejector which extends below 65 the slide 13.

The guide-spring 8, igniter 9 10, and the holding-dog 12 are preferably formed in one

piece or strip bent as shown in Fig. 1 and secured to the bottom of the box by means of a tongue 14, struck up therefrom and passing 70 through a suitable orifice in the strip of which these springs, &c., are composed, thus holding the strip from outward movement while its position with relation to the other parts of the mechanism is maintained by 75 means of a lug 15, also struck up from the bottom of the box and bearing against a portion of the strip, so as to combine with the tongue 14 in holding it against lateral twisting. The end of the strip opposite to that on 80 which the igniter 9 is formed is rounded off from the holding-dog 12, as shown at 16, so as to form a guide for directing the matches up between the ejecting-point 6 and the guide-spring 8.

The spring-tongue 11 may be formed by simply leaving the edges of the upper end of the box unsecured. The free end of the tongue 11 is provided with a notch 17, which enables the tongue to close partially around 90 the ejecting-point 6 after the match has cleared the end of the box, thus enabling such point to be withdrawn without pulling any of the burned match back into the box. Such notch 17 also avoids possibility of damage to the point 6 from being protruded at a time when there are no matches in the box. 95

The ignition of the head 4 is caused by the igniter 9, which is of pointed form, as shown in Fig. 6, dropping off, as it were, from the edge of the head as the latter leaves the point, and to the end that sufficient concussion may be produced for accomplishing this I provide the lower side of the head 4 with a cavity 4^a, into which the point 9 rapidly descends and 100 in doing so scrapes against and ignites the head 4. This cavity 4^a, however, is only desirable when the igniting-head 4 is arranged at the upper or outer end of the match-body 3, and is even then merely the equivalent of 105 an abrupt shoulder at the lower edge of the head. When, however, the head 4 is arranged at the lower end of the match-body 3, the point 9 will drop off the edge with sufficient 110 rapidity to ignite the head. This opposite 115 arrangement of the head 4 is shown in Fig. 8.

Having thus described my invention, what I claim as new therein, and desire to secure by Letters Patent, is—

1. An automatic lighter having in combination a box or receptacle for containing a strip of connected matches, an ejector for forcing said matches from said box, said box being provided with an opening and a spring-tongue closing said opening, and an igniter 120 having a portion adapted to bear against and deflect said tongue before the latter is reached by the match, substantially as set forth.

2. An automatic lighter having in combination a box or receptacle for containing a strip of connected matches, an ejector, a flexible guide arranged adjacent to the line of movement of said ejector, a dog arranged at the lower or inner end of said guide for pre-

venting retrograde movement of the match, and an igniter arranged at the other end of said guide, substantially as set forth.

3. An automatic lighter having in combination a box or receptacle for containing a strip of connected matches, and being provided at one end with an opening and a spring-tongue closing said opening, an ejector for forcing said matches through said opening and means for deflecting said tongue and igniting the match before the latter reaches the tongue, substantially as set forth.

4. An automatic lighter having in combination a box or receptacle for containing a number of connected matches, an ejector having a point for ejecting said matches, said box being provided with an opening for the passage of the matches and a spring-tongue for closing said opening and having a notch adapted to fit around said point after the match is ejected, and an igniter arranged in the line of movement of the match, substantially as set forth.

5. An automatic lighter having in combination a box or receptacle, an ejector arranged against one side thereof and having a slide 13 turned over and embracing said side, and a cover to said box fitting against said ejector and holding the same in place, substantially as set forth.

6. An automatic lighter having in combination a box or receptacle, an ejector consisting of a flat strip arranged against one side thereof and having a slide 13 turned over and embracing said side, and a cover for said box having the cut-away portion 14 forming a slot for the movement of said slide, said ejector having a portion projecting beyond or below said slot and fitting under said cover, substantially as set forth.

7. An automatic lighter having in combina-

tion a box or receptacle, an ejector, the igniter 9, guide-spring 8 and spring-dog 12 formed in one piece and secured in said box, substantially as set forth.

45

8. An automatic lighter having in combination a box or receptacle, an ejector, a spring-strip having one end pointed and arranged adjacent to the line of movement of said ejector and constituting an igniter, the intermediate portion of said strip being doubled backwardly upon itself to form the spring-guide 8 adjacent to the line of movement of said ejector and the spring-dog 12 composed of a tongue struck up from said strip and projecting toward said ejector, substantially as set forth.

50

9. An automatic lighter having in combination a box or receptacle, an ejector, a spring-strip bent to form an igniter 9 and guide-spring 8, a tongue struck up from the bottom of said box and passing through said spring-strip and the lug 15 struck up from said box and bearing against said strip at another point, substantially as set forth.

65

10. An automatic lighter having in combination a box or receptacle, an ejector, a strip having one end pointed to form the igniter 9, bent to form the shoulder 10, doubled back upon itself to form the guide-spring 8 adjacent to the line of movement of the ejector, the dog 12 struck up from said strip and the guide 16 rounded off from said dog, and a spring-tongue for closing the aperture of the box arranged adjacent to a part of said strip and adapted to be deflected thereby, substantially as set forth.
